UNITED STATES PATENT OFFICE

ROBERT E. KENNEDY, OF CHICAGO, ILLINOIS, ASSIGNOR TO THE BRUNSWICK-BALKE-COLLENDER COMPANY, OF CHICAGO, ILLINOIS, A CORPORATION OF DELAWARE

ADJUSTABLE PIN SPOT FOR BOWLING ALLEYS

Application filed July 2, 1930. Serial No. 465,309.

This invention relates to an adjustable pin setter and spotter for bowling alleys and has for one of its principal objects the provision of means for setting or spotting pins on bowling alleys, which means shall be conveniently adjustable to a changed level of the surface of the bowling alley when the same is planed or ground down during the process of re-smoothing or re-finishing.

One of the important objects of this invention is to provide an adjustable pin setter and spotter for bowling alleys or the like whereby that portion of the floor or bowling alley surface upon which the pins are placed, and which is usually of a different consistency and material than the floor proper, can be vertically adjusted so as to accommodate itself to the varying levels of the floor when ground down, while at the same time eliminating the necessity of grinding or re-finishing the surface of the pin setter element itself.

Still another and further important object of this invention is to provide an adjustable portion of any surface that can be conveniently varied with respect to the plane of the remainder of the surface when said remainder is changed in level or contour by any necessary operation.

Other and further important objects of the invention will be apparent from the disclosures in the accompanying drawing and following specification.

The invention, in a preferred form, is illustrated in the drawing and hereinafter more fully described.

In the drawing—

Figure 1 is a top plan view of the improved adjustable pin setter and spotter of this invention, showing the same as incorporated into the floor of a bowling alley or the like.

Figure 2 is a vertical sectional view taken on the line 2—2 of Figure 1.

Figure 3 is a horizontal section on the line 3—3 of Figure 2, looking in the direction indicated by the arrows.

Figure 4 is a perspective view of the device when removed.

Figure 5 illustrates a slight modification of the invention as adapted to a pin setting apparatus.

As shown in the drawing—
The reference numeral 10 indicates, generally, the floor of a bowling alley or the like, or any other surface to which this invention may be adapted. The adjustable pin 55 setter and spotter of this invention includes essentially an upper surface 12, preferably in the form of a disk, as shown, and also preferably of some material other than the material of the bowling alley floor, which may be of fiber or any other desired or convenient material which is readily distinguishable from the remaining floor surface.

Heretofore in re-finishing the surface 10 of the bowling alley, the surface 12 of the pin spotting element was also necessarily re-finished, thereby producing an undesirable result in the form of a rough spot or the like. The object of the present invention is to supply a spot which need not be re-finished on its surface, but which can be conveniently adjusted downwardly as the surrounding surface is worn away, and which, furthermore, is positively maintained in desired adjusted position.

In the preferred embodiment of the present invention the disk 12 is in turn mounted upon a member 14 which comprises essentially an upper plate, preferably of metal, of the same diameter as the disk 12 and which terminates in a downwardly extending screw-threaded shank 16 of approximately half the diameter of the disk 12 and the upper plate 14. This screw-threaded shank is mounted in a correspondingly screw-threaded metal plate 18, which is positioned at the bottom of a suitable well or the like 20 formed in the surface of the bowling alley floor for the proper reception of the device. This plate is suitably affixed in position at the bottom of the well by means of screws or the like 22. This plate is provided with a plurality of up-standing integral lugs 24 mounted on its periphery, as best shown in Figures 3 and 4, these lugs being preferably mounted in pairs on opposite sides of the device, as shown, and in the space between each pair is fitted a correspondingly downwardly extending lug 26 which is attached to or integral with a plate 28 provided with

a central opening so as to fit around the threaded shank 16 and mounted loosely thereon. A helical spring 30 surrounds the screw-threaded shank 16 and is positioned between 5 plates 18 and 28 so as to normally force the plate 28 upwardly and into contacting relation with the under-face of the element 14. A suitable upstanding cylindrical portion 32 is provided on the plate 18, and preferably 10 integral therewith, being interiorly screw-threaded so as to receive the shank 16.

A set of up-standing lugs 34 is provided on the periphery of the plate 28, these lugs being preferably integral therewith and adapted 15 to selectively fit into certain of a plurality of corresponding notches 36 formed in the lower periphery of the element 14. It will be observed that when the lugs 34 are in the notches 36, no rotation of the disk 12 or its attached 20 plate 14 together with the integral shank 16 can take place, owing to the fact that the lugs 26 will contact with the lugs 24 of the fixed plate 18 after a very limited rotative movement of the first named elements.

25 In order to allow of such rotation when desired or necessary, a pair of openings 40 is provided in the disk 12 and plate 14, these openings being adapted for the insertion thereinto of correspondingly shaped and 30 spaced prongs 42 of an operating key or the like 44, the prongs being of a sufficient length so that when inserted into the openings 40 to their fullest extent the ends will contact with the upper face of the plate 28 and depress 35 the same sufficiently so as to move the lugs 34 from contacting relation with the openings or sockets 36. This position is illustrated in Figures 2 and 4. Very obviously a rotative movement of the combined elements 40 12, 14, and 16 will then be possible, allowing of a suitable adjustment of the level of the upper face of the disk 12 with respect to the surrounding floor surface 10. When the key 45 elements are withdrawn, the spring 30 will return the plate 24 and its attached lugs to contacting relation with the lower face of the plate 14, and if a suitable interfitting of the lugs 34 into the sockets 36 does not immediately take place, this can be accomplished 50 by further slight rotation of the disk 12 with the key-prongs 42 in a position slightly withdrawn from the openings 40.

55 In Figure 5 is illustrated a slight modification of the invention, wherein a pin setter rod or the like 50 is passed upwardly through a central opening 52 in the elements 12-a and 16-a.

60 It will be evident that herein is provided a convenient and readily operable means for varying the height relation of two associated surfaces and at the same time positively locking the resultant relationship. This is especially desirable when one surface is being continually worn off, the other surface being 65 of a different material and thereby re-

ceiving a different degree of wear. The adjustment is such as to be suitably and positively regulated and definitely fixed. Further, one surface can be depressed out of harm's way while the surrounding surface is being dressed.

70 I am aware that many changes may be made and numerous details in the construction varied throughout a wide range, without departing from the principles of this invention, and I therefore do not purpose limiting the patent granted hereon otherwise than as necessitated by the prior art.

75 I claim as my invention:

80 1. An adjustable pin spot for bowling alleys, including a plate set into the bowling alley surface and adjustable with respect to the plane of said surface, together with means for locking the plate in such adjusted position, said means comprising a support for the plate, mounted in an opening counter-sunk in the alley surface, and depressible latching means between the support and the plate.

85 2. An adjustable pin spot for bowling alleys, including a plate set into the bowling alley surface and adjustable with respect to the plane of said surface, together with means for locking the plate in such adjusted position, said means comprising a support for the plate, mounted in an opening counter-sunk in the alley surface, and depressible latching means between the support and the plate; the support including a plate adapted to be mounted in the base of said opening, 90 said plate having a screw-threaded opening therein, a supporting shaft, correspondingly screw-threaded, mounted in the plate, and means for normally preventing rotation of the support.

95 3. An adjustable pin spot for bowling alleys, including a plate set into the bowling alley surface and adjustable with respect to the plane of said surface, together with means for locking the plate in such adjusted position, said means comprising a support for the plate, mounted in an opening counter-sunk in the alley surface, and depressible latching means between the support and the plate; the support including a plate adapted to be mounted in the base of said opening, 100 said plate having a screw-threaded opening therein, a supporting shaft, correspondingly screw-threaded, mounted in the plate, and means for normally preventing rotation of the support.

105 4. An adjustable pin spot for bowling alleys, including a plate set into the bowling alley surface and adjustable with respect to the plane of said surface, together with means for locking the plate in such adjusted position, said means comprising a support for the plate, mounted in an opening counter-sunk in the alley surface, and depressible latching means between the support and the plate; the support including a plate adapted to be mounted in the base of said opening, 110 said plate having a screw-threaded opening therein, a supporting shaft, correspondingly screw-threaded, mounted in the plate, and means for normally preventing rotation of the support; said latching means comprising a plate loosely mounted about the said screw-threaded shaft, downwardly extending lugs on the plate, adapted to contact with corresponding lugs on the supporting plate, and upwardly extending lugs on the plate, adapted to fit into notches in the support.

115 5. An adjustable pin spot for bowling alleys, including a plate set into the bowling alley surface and adjustable with respect to 120

the plane of said surface, together with means for locking the plate in such adjusted position, said means comprising a support for the plate, mounted in an opening countersunk in the alley surface, and depressible latching means between the support and the plate; the support including a plate adapted to be mounted in the base of said opening, said plate having a screw-threaded opening therein, a supporting shaft, correspondingly screw-threaded, mounted in the plate, and means for normally preventing rotation of the support; said latching means comprising a plate loosely mounted about the said screw-threaded shaft, downwardly extending lugs on the plate, adapted to contact with corresponding lugs on the supporting plate, upwardly extending lugs on the plate, adapted to fit into notches in the support, and a helical spring for normally maintaining said loosely positioned plate in locking contact with the pin support.

5. An adjustable pin spot for bowling alleys, including a plate set into the bowling alley surface and adjustable with respect to the plane of said surface, together with means for locking the plate in such adjusted position, said means comprising a support for the plate, mounted in an opening countersunk in the alley surface, and depressible latching means between the support and the plate; the support including a plate adapted to be mounted in the base of said opening, said plate having a screw-threaded opening therein, a supporting shaft, correspondingly screw-threaded, mounted in the plate, and means for normally preventing rotation of the support; said latching means comprising a plate loosely mounted about the said screw-threaded shaft, downwardly extending lugs on the plate, adapted to contact with corresponding lugs on the supporting plate, upwardly extending lugs on the plate, adapted to fit into notches in the support, a helical spring for normally maintaining said loosely positioned plate in locking contact with the pin support, and a manually operated key for first depressing said plate against the action of the spring and then rotating the pin setter in its screw-threaded support.

6. An adjustable pin spot for bowling alleys, including a plate set into the bowling alley surface and adjustable with respect to the plane of said surface, together with means for locking the plate in such adjusted position, said means comprising a support for the plate, mounted in an opening countersunk in the alley surface, and depressible latching means between the support and the plate; the support including a plate adapted to be mounted in the base of said opening, said plate having a screw-threaded opening therein, a supporting shaft, correspondingly screw-threaded, mounted in the plate, and means for normally preventing rotation of

the support; said latching means comprising a plate loosely mounted about the said screw-threaded shaft, downwardly extending lugs on the plate, adapted to contact with corresponding lugs on the supporting plate, upwardly extending lugs on the plate, adapted to fit into notches in the support, a helical spring for normally maintaining said loosely positioned plate in locking contact with the pin support, and a manually operated key for first depressing said plate against the action of the spring and then rotating the pin setter in its screw-threaded support when freed from locking position. 70 75

In testimony whereof I affix my signature. 80
ROBERT E. KENNEDY.

5. An adjustable pin spot for bowling alleys, including a plate set into the bowling alley surface and adjustable with respect to the plane of said surface, together with means for locking the plate in such adjusted position, said means comprising a support for the plate, mounted in an opening countersunk in the alley surface, and depressible latching means between the support and the plate; the support including a plate adapted to be mounted in the base of said opening, said plate having a screw-threaded opening therein, a supporting shaft, correspondingly screw-threaded, mounted in the plate, and means for normally preventing rotation of the support; said latching means comprising a plate loosely mounted about the said screw-threaded shaft, downwardly extending lugs on the plate, adapted to contact with corresponding lugs on the supporting plate, upwardly extending lugs on the plate, adapted to fit into notches in the support, a helical spring for normally maintaining said loosely positioned plate in locking contact with the pin support, and a manually operated key for first depressing said plate against the action of the spring and then rotating the pin setter in its screw-threaded support.

6. An adjustable pin spot for bowling alleys, including a plate set into the bowling alley surface and adjustable with respect to the plane of said surface, together with means for locking the plate in such adjusted position, said means comprising a support for the plate, mounted in an opening countersunk in the alley surface, and depressible latching means between the support and the plate; the support including a plate adapted to be mounted in the base of said opening, said plate having a screw-threaded opening therein, a supporting shaft, correspondingly screw-threaded, mounted in the plate, and means for normally preventing rotation of
